DESIGN FOR A STATUETTE

Morris Mescon, Bronx, and Oscar W. Doctor,
New York, N. Y.

Application June 25, 1934, Serial No. 52,338

Term of patent 3½ years

To all whom it may concern:

Be it known that we, Morris Mescon and Oscar W. Doctor, both citizens of the United States, residing at Bronx, New York, and New York city, in the counties of Bronx and New York, respectively, and both in the State of New York, have invented a new, original, and ornamental Design for Statuettes, of which the following is a specification, reference being had to the accompanying drawing, forming part thereof.

We claim:

The ornamental design for a statuette as shown.

In testimony whereof we have affixed our signatures.

MORRIS MESCON.
OSCAR W. DOCTOR.
